UNITED STATES PATENT OFFICE

119,063

DESIGN FOR AN AUTOMOTIVE MERCHANTISING SERVICE CABINET

Alexander P. Fox, University City, and August Daniel Reisert, St. Louis, Mo., assignors to Lincoln Engineering Company, St. Louis, Mo., a corporation of Missouri

Application November 18, 1939, Serial No. 88,362

Term of patent 7 years

To all whom it may concern:

Be it known that we, Alexander P. Fox and August Daniel Reisert, citizens of the United States, and residents of University City, St. Louis County, Missouri, and St. Louis, Missouri, respectively, have invented a new, original, and ornamental Design for an Automotive Merchandising Service Cabinet, of which the following is a specification, reference being had to the accompanying drawing, forming part thereof, in which

Fig. 1 is a top plan view;

Fig. 2 is a front elevational view; and, Fig. 3 is a side elevational view, taken from the right of Fig. 2, of an automotive merchandising service cabinet, showing our new design.

The rear of the cabinet is plain.

We claim:

The ornamental design for an automotive merchandising service cabinet, substantially as shown and described.

ALEXANDER P. FOX.
AUGUST DANIEL REISERT.
